WIRE LOOP FORMING DEVICE

Filed July 10, 1940

INVENTOR: ⁴³
JOHN HEIDRICH.
BY Martin J. Smith, ATTY.

UNITED STATES PATENT OFFICE

2,236,503

WIRE LOOP FORMING DEVICE

John Heidrich, Los Angeles, Calif.

Application July 10, 1940, Serial No. 344,751

7 Claims. (Cl. 140—123)

My invention relates to a wire loop forming device and the invention herein disclosed is an improvement on the wire loop forming device forming the subject matter of my copending application for U. S. Letters Patent filed March 27, 1940, Serial No. 326,253.

The principal objects of my present invention are, to generally improve upon and simplify the construction of the device disclosed in my aforesaid copending patent application, further, to provide a wire loop forming device particularly designed for use in twisting wire to form loops that receive and fasten fishhooks, swivels, or the like, and further, to provide simple and efficient means that will impart the necessary degree of tension to that portion of the wire that is being twisted to form a loop.

A further object of my invention is, to provide a device of the character referred to having tension producing means that may be easily and quickly adjusted for producing the desired degree of tension for wires of different sizes that are acted upon and twisted to provide loops.

With the foregoing and other objects in view, my invention consists in certain novel features of construction and arrangement of parts that will be hereinafter more fully described and claimed and illustrated in the accompanying drawing in which:

Fig. 1 is a side elevational view of a wire loop forming device constructed in accordance with my invention.

Fig. 2 is a detail horizontal section taken on the line 2—2 of Fig. 1.

Fig. 3 is a horizontal section taken on the line 3—3 of Fig. 1.

Fig. 3A is an enlarged cross section taken on the line 3A—3A of Fig. 3.

Fig. 4 is a horizontal section taken on the line 4—4 of Fig. 1.

Fig. 5 is an elevational view of a modified form of the adjustable tension arm forming a part of the wire twisting device.

Fig. 6 is a plan view of the modified form of the adjustable tension producing arm.

Fig. 7 is a vertical cross section taken on the line 7—7 of Fig. 6.

Referring by numerals to the accompanying drawing which illustrates a preferred embodiment of my invention, 10 designates a flat bar that provides a support for the operating parts of the device and formed in said bar near one end is a pair of reversely arranged keyhole-shaped apertures 11 for the reception of screws 12 that are seated in a supporting member 13,

thus firmly holding the bar in horizontal position. Obviously, other means may be utilized for supporting the bar in horizontal position.

Formed on the end of bar 10 opposite from the openings 11 is a vertically disposed bearing 14 for a shaft 15, the upper end of which is formed into a crank handle 16 and the lower end of said shaft terminating in an upturned hook 17 for the reception of a fishhook or the member that is connected to the loop formed in a section of wire by the device.

Formed in the intermediate portion of bar 10 is a pair of vertically disposed channels 18 that receive the parallel legs of an elongated U-shaped member 19, preferably formed from a single piece of heavy wire, and this member is adjustably mounted on bar 10 by means of a bolt 20 that passes through bar 10 and through a washer 21 and the latter being clamped against the legs of member 19 by a winged nut 22 that is seated on the threaded end of bolt 20.

Mounted for vertical adjustment on the member 19 is a metal plate 23, one vertical edge of which is bent at right angles to form a flange 24, and formed in the vertical edge of said flange is a series of notches 25. A bolt 26 passes through plate 23 between the legs of member 19 and screw seated on the threaded portion of said bolt and positioned between the legs of member 19 is a nut 27.

A clamping plate 28 is provided with an aperture for the reception of bolt 26 and the ends of this plate above and below the nut 27 are bent slightly toward plate 23 so as to engage the legs of member 19. A winged nut 29 is screw seated on the threaded end of bolt 26 and when this winged nut is tightened, the plates 23 and 28 are clamped upon the legs of member 19 in properly adjusted position.

One end of a tension arm 30 is pivotally mounted on bolt 26 adjacent plate 23 and mounted on said bolt between the head thereof and said arm is a torsional coil spring 31. From the end of this spring adjacent the head of bolt 26 an arm 32 projects outwardly past the notched edge of flange 24 and the outer end of said arm terminating in a loop 33. This arm 32 may be moved vertically along the notched edge of flange 24 and engaged in any one of the notches thereof, thereby varying the degree of torsional strains of spring 31 and consequently providing means for regulating the tension of arm 30 as the same swings upward during the wire loop forming operations.

The end of the section of wire forming spring

31 and arm 32 opposite the end that is extended to provide said arm is extended alongside the arm 30 and the terminal portion of this extension is bent at right angles as designated by 34 and such bent portion extends through an aperture 35 that is formed in arm 30. This portion 34 is adapted to engage against the vertical edge of plate 23 opposite the edge provided with the flange 24, thereby forming a stop to limit the downward swinging movement of the tension 10 arm.

Projecting outwardly from the upper edge of arm 30 and disposed at right angles thereto is a flange 35 and from the outer edge of this flange the material forming the tension arm, and which is preferably sheet metal, is rebent and extended over the flange 35 to form a transversely inclined flange 36. The space 37 between the flanges 35 and 36 gradually decreases in width to the point where said flanges unite, thus providing space for different sizes of wire that are mounted upon the tension arm and which are twisted to form loops. 15

At the outer end of arm 30, the end of the overlying flange 36 is separated along its side edge from the corresponding edge of the underlying flange 35 and the material in the end of flange 36 along this line of separation is bent upwardly to form an inclined lip 38. 20

Formed in the edge of this lip adjacent the point where the same unites with the flange 36 is a notch 39 for the reception of that portion of the wire that is formed into a coil. 25

Formed in the intermediate portion of flange 36 on the opposite side from the notch 39 is a 30 pair of spaced wire receiving notches 40.

Where my improved device is utilized for forming a loop from wire that passes through the eye of a fishhook, a portion of the wire adjacent the end of the section utilized passes through one or both of the notches 40, thence lengthwise through the tapered space between the flanges 35 and 36, thence upwardly through notch 39, 35 through the eye of the fishhook, and from the latter the wire extends downward alongside the free end of the tension arm 30.

The arm 32 that projects from the end of spring 31 is now adjusted on the notched edge of flange 24 so as to impart torsional strains to spring 31 and consequently establishing the proper degree of tension or resistance to upward swinging movement of the arm 30 to correspond with the size of the wire that is being twisted to form a loop that engages the eye of the hook. 40

Crank handle 16 is now engaged and rotated, thereby rotating the fishhook that is engaged by and suspended from hook 17, and such action coils that portion of the wire between the eye of the fishhook and the notch 39 around the adjacent parallel portion of the wire and this coiling action is yieldingly resisted by the tension imparted to arm 30 by the spring 31 and also by the frictional contact of that portion of the wire that is positioned between the notches 39 and 40 and the underlying and overlying flanges 35 and 36 respectively. 45

Due to the fact that the tension arm 30 is inclined downwardly from its pivot point and the wire passes from the space 37 upwardly through notch 39, said wire as it is drawn from the space 37 will form a tight coil about that portion of the wire that depends from the eye of the fishhook downwardly past the free end of the tension arm and as such coil progresses, the end portion of the wire will be drawn through 50

the notches 39 and 40 and through space 37 until the coil has reached the eye of the fishhook. 55

The coiling operation is terminated a short distance from the eye of the hook and thus a loop is provided that passes through and secures the eye of the hook to the wire and which latter provides a leader between the hook and line. Obviously, the device may be used in forming loops at the ends of wires that engage rings, swivels, and the like.

To increase the torsional strains in spring 31 and consequently increase the tension or resistance to upward movement of the arm 30, it is only necessary to move the outer end of arm 32 upward and engage it in one of the upper notches 25 in flange 24 and which procedure is carried out when the device is utilized for forming loops in the larger sizes of wire.

In the modified construction illustrated in Figs. 5, 6, and 7, a tension arm 43 is pivoted at one end to a plate 44 that corresponds with plate 23 and which is adjustably mounted on member 19 and the outer portion of said arm 43 is provided with a flange 45 that is disposed substantially at right angles to said arm. 20

Arranged beneath the flange 45 and projecting through an opening 46 that is formed in the upper portion of arm 43 is a transversely disposed plate 47. That portion of the plate that projects through opening 46 is rebent so as to provide an inclined lip 48 that underlies the plate 47 and thus, a wedge-shaped space 49 is formed between said lip and the adjacent portion of the plate for the accommodation of wires of different sizes. 30

Passing downwardly through flange 45 and through a short longitudinally disposed slot 50 that is formed in plate 47 is a bolt 51 on the threaded end of which is located a nut 52. An expansive coil spring 53 is arranged on bolt 51 between the nut 52 and the under side of plate 47. 40

Lips 54 are pressed downwardly from flange 45 to the sides of plate 47, thereby providing guides for said plate in its transverse sliding movement beneath said flange and the spring 53 bearing against the under side of the sliding plate produces a certain degree of yielding pressure that resists such sliding movement. 45

Where this form of tension arm is utilized, the wire that is to be twisted to form a loop has its end portion extended through the wedge-shaped space 49 and from the edge of the plate the wire extends upwardly, thence through the eye of the fishhook or swivel, thence downwardly past the free end of the tension arm. 50

Thus it will be seen that I have provided a wire loop forming device that is relatively simple in construction, inexpensive of manufacture and very effective in performing the functions for which it is intended. 60

It will be understood that minor changes in the size, form and construction of the various parts of my improved wire loop forming device, may be made and substituted for those herein shown and described, without departing from the spirit of my invention, the scope of which is set forth in the appended claims. 65

I claim as my invention:

1. In a wire loop forming device, a support, a shaft journaled on said support, a hook on the lower end of said shaft, a member mounted for vertical adjustment on said support, a plate mounted for vertical adjustment on said member, an arm pivoted on said plate, means on said

arm for receiving and holding a wire that is to be twisted to form a loop and adjustable means for yieldingly resisting upward swinging movement of said arm.

2. In a wire loop forming device, a support, a shaft journalled on said support, a hook on the lower end of said shaft, a member mounted for vertical adjustment on said support, a plate mounted for vertical adjustment on said member, an arm pivoted on said plate, the free end of which arm terminates at a point below the hook on said shaft, the upper portion of said arm being provided with a slot that is wedge-shaped in cross section for the accommodation of wires of different sizes and adjustable means for yieldingly resisting upward swinging movement of said arm.

3. A wire loop forming device as set forth in claim 2 and there being wire receiving notches formed in the upper portion of said arm above the wedge-shaped space therein.

4. In a wire loop forming device, a support, a vertically disposed shaft journalled on one end of said support, a hook on the lower end of said shaft, a member depending from said support, a plate adjustably mounted on said depending member, a bolt carried by said plate, an arm pivoted on said bolt and projecting outwardly and downwardly therefrom to point beneath said shaft, means on the outer portion of said arm

for receiving and holding a wire, a torsional spring on said bolt, one end of which spring is seated in said pivoted arm, an arm projecting from the other end of said spring, a flange on said plate and the free edge of which flange is notched for the reception of the arm that projects from said spring.

5. In a wire loop forming device, a substantially T-shaped support, means on the horizontal portion of said support for rotating a member to which a loop of wire is to be attached, a plate adjustably mounted on the vertical portion of said support, an inclined arm pivotally mounted at one end on said plate, the free lower end of which arm occupies a position below said rotating means and means associated with the pivoted end of said arm and said support for yieldingly resisting the upward swinging movement of said arm.

6. A wire loop forming device as set forth in claim 5 and with means on said arm for receiving and holding the wire that is to be twisted to form a loop that engages the member carried by said rotating means.

7. A wire loop forming device as set forth in claim 5 and with means for limiting the downward swinging movement of said arm.

JOHN HEIDRICH.
